(57) **CLAIM**

The ornamental design for a display screen or portion thereof with graphical user interface as shown and described.

DESCRIPTION

FIG. 1 is a front view of a display screen or portion thereof with graphical user interface according to a first embodiment of our new design;

FIG. 2 is a front view of a display screen or portion thereof with graphical user interface according to a second embodiment of our new design;

FIG. 3 is a front view of a display screen or portion thereof with graphical user interface according to a third embodiment of our new design;

FIG. 4 is a front view of a display screen or portion thereof with graphical user interface according to a fourth embodiment of our new design;

FIG. 5 is a front view of a display screen or portion thereof with graphical user interface according to a fifth embodiment of our new design;

FIG. 6 is an additional view of FIG. 1 but shown with the broken lines illustrating portions of the graphical user interface removed for clarity of illustrating the claimed design;

FIG. 7 is an additional view of FIG. 2 but shown with the broken lines illustrating portions of the graphical user interface removed for clarity of illustrating the claimed design;

FIG. 8 is an additional view of FIG. 3 but shown with the broken lines illustrating portions of the graphical user interface removed for clarity of illustrating the claimed design;

FIG. 9 is an additional view of FIG. 4 but shown with the broken lines illustrating portions of the graphical user interface removed for clarity of illustrating the claimed design;

FIG. 10 is an additional view of FIG. 5 but shown with the broken lines illustrating portions of the graphical user interface removed for clarity of illustrating the claimed design.

The dot-dash broken lines showing the display screen or portion thereof form no part of the claimed design. The dashed broken lines showing portions of the graphical user interface form no part of the claimed design.

1 Claim, 10 Drawing Sheets
